[57] CLAIM

The ornamental design for a hand manipulated exercise device, as shown and described.

DESCRIPTION

FIG. 1 is a top plan view of a hand manipulated exercise device, showing my new design;

FIG. 2 is a side elevational view thereof, the opposite side being a mirror image;

FIG. 3 is a bottom view thereof;

FIG. 4 is an end elevational view thereof; the opposite end being a mirror image;

FIG. 5 is a top plan view of another embodiment of a hand manipulated exercise device, showing a variation of my new design;

FIG. 6 is a side elevational view thereof, the opposite side being a mirror image;

FIG. 7 is a bottom view thereof;

FIG. 8 is an end elevational view thereof, the opposite end being a mirror image;

FIG. 9 is a top plan view of yet another embodiment of a hand manipulated exercise device, showing a further variation of my new design;

FIG. 10 is a side elevational view thereof, the opposite side being a mirror image;

FIG. 11 is a bottom view thereof; and

FIG. 12 is an end elevational view thereof, the opposite end being a mirror image.

FIG. 1FIG. 2FIG. 3FIG. 4
